UNITED STATES PATENT OFFICE.

WILLIAM P. NEIGHBORS, OF DES ARC, ARKANSAS.

JOURNAL-BOX.

1,117,426.

Specification of Letters Patent. Patented Nov. 17, 1914.

Application filed April 28, 1914. Serial No. 835,003.

To all whom it may concern:

Be it known that I, WILLIAM P. NEIGHBORS, citizen of the United States, residing at Des Arc, in the county of Prairie and State of Arkansas, have invented certain new and useful Improvements in Journal-Boxes, of which the following is a specification, reference being had therein to the accompanying drawing.

10 This invention relates to certain improvements in journal boxes or bearings, and has more particular reference to novel and improved means of lubrication for devices of this character.

15 In the 2 to which the present invention relates, it has been found quite difficult to obtain a journal box that will answer all of the requirements of simplicity, economy, and adequate lubrication of the various portions of the journal, and one of the primary 20 objects of my invention is to overcome existing difficulties in the provision of a comparatively inexpensive device for the described purpose, involving but few parts, while 25 positive in its oil distributing and lubricating characteristics, and at the same time to provide a device that will be strong, durable and otherwise highly efficient in service.

One of the main features of the invention 30 resides in the provision of novel and improved oil conveying means, having operatively associated means whereby the oil when picked up from its chamber in the journal box, will be maintained in position 35 on said conveying means until the latter reaches its point of discharge.

More particularly, in this connection, the invention includes a rotatable carrier or conveyor having a series of oil receptacles, and 40 a closure means for said receptacles, the said closure means being of a character to permit one or more of said receptacles to receive oil from the oil reservoir and to be thereafter closed until they have reached an operative 45 position with respect to the parts to be lubricated, when the oil will automatically discharge from said receptacles.

Another feature of the invention resides 50 in the provision of novel means for supporting the oil carrying parts in position, to the end that while an automatic self-oiling journal box is obtained, at the same time the oil will be fed to the journal only when the

latter is subjected to movement, the oil otherwise remaining at a state of rest.

The invention further embodies a novel and improved construction of brass, and associated oil distributing means having in view the proper application of the oil at the desired points about the periphery of the journal.

Still further, the invention comprehends a novel construction of journal box, one readily applicable to various types of constructions, and one wherein convenient access to the interior or working parts thereof is obtained.

Other and further improvements and novel details in the construction and arrangement of the various parts will be appreciated from the description to follow, which, for a clear understanding of the invention, should be considered in connection with the accompanying drawing, which form a part hereof, and wherein is disclosed, for the purpose of illustration, a convenient and satisfactory embodiment of the invention.

In the drawings:—Figure 1 is a vertical longitudinal section view; Fig. 2 is a transverse sectional view on line 2—2 of Fig. 1, looking in the direction of the arrow; Fig. 3 is a similar view on line 3—3, of Fig. 1, looking in the direction of the arrow; Fig. 4 is a face view of the disk-shaped member 27; Figs. 5 and 6 are detail views of the wedge member; Figs. 7 and 8 are detail views of the brass member.

With more particular reference to the drawings, wherein like reference numerals 90 denote corresponding parts throughout the several views, a journal box casing is provided, the same including an inner substantially rectangular portion 1 having relatively flat sides 2, and an inner end wall 3, 95 the latter having a substantially centrally arranged opening 4, adapted for the reception of the end of a rotatable shaft 5. The top and bottom walls of said casing adjacent said end wall 3 have slotted ways adapted 100 for the reception of dust guard 6, the inner ends of which are curved to correspond to the curvature of the shaft 5. The wall 1 connects with a substantially cylindrical enlarged wall 7. The sides of the wall 1 adjacent the top thereof have on their inner

end surfaces, abutment pieces 8, shown in dotted lines in Fig. 3, and the top wall of the casing 1 is upwardly flared on its inner surface, as indicated at 9. 10 designates a brass proper, the same being curved upon its inner face to correspond to the curvature of the journal 11, the said brass having laterally extending shoulders 12, adjacent the rear end thereof adapted to contact with the 15 end of the abutments 8, and the inner end of said brass being adapted to contact with the inner surface of the end wall 3 of the casing, said inner end of the brass having on its upper surface a tapered portion 14 20 adapted to be engaged by a similar tapered portion 15 of a wedge block 16 which latter is adapted, when in position in the journal, to rest upon the brass. The wedge block 16 has intermediate its sides on its upper surface an inclined projection 17, adapted to engage the flared wall 9 of the top of the casing 1. The top of the brass is provided with a substantially rectangular recessed portion 18 adapted to receive a similarly 25 shaped downward projection 19 on the wedge block, whereby to provide an interlocking engagement between these parts. The sides of the wedge block are extended, at 20, whereby to provide abutments to engage the abutments 8 on the sides of the casing 1. The wedge block and brass are of a construction to properly distribute the oil to the proper places about the periphery of the journal 11, and to this end the inclined portion 17 of the wedge block is provided with an opening 21, extending longitudinally therethrough, at an incline toward the inner surface of the wedge block, the opening 21 having at its outer end an enlarged 30 inlet port 22, and at its inner end communicating with an elongated recess, 23, in the rectangular projection 19. The recessed portion 18 of the brass is provided with longitudinally spaced openings 24 for the outlet of the oil, each opening communicating with oppositely projecting laterally extending oil ways 25, an additional longitudinally extending way 26 being provided between the openings 24. These oil ways provide 35 means for feeding the oil substantially from end to end of the journal and entirely about the circumference of the latter in the rotary movement thereof. Likewise the oil will be evenly distributed to the journal which is 40 not the case where the oil is delivered to the journal at its end.

The means for conveying the oil to the inlet opening 22 of the distributing port leading to the brass, in the preferred embodiment of my invention illustrated, is substantially as follows:—A disk shaped member 27 preferably circular in form having a diameter slightly less than that of the cylindrical wall 7 is provided, the same having a centrally arranged recess in one face 45 thereof adapted to receive the end of the journal. The said disk is also provided with an annular recess adjacent the periphery thereof, said recess being separated by walls or partitions 30, whereby to provide a plurality of closely associated oil receptacles 29. The open face of the receptacles 29 are so positioned with respect to the inlet 22 of the wedge block as to register therewith in the rotary movement of the conveyer disk, 50 it being understood that the said disk is adapted to be connected to the end of the journal 11 and continuously rotate with the latter. In the rotation of the disk, the oil will be lifted up from the oil chamber provided below the journal in the journal box, but it has been ascertained in practice that means should be provided to prevent the oil, as it is being fed by the disk 27, falling out of the receptacles 29, with the result that 55 only a small quantity thereof might be delivered to the distributing ports of the brass.

A novel means for preventing the premature discharge of the oil from the receptacles 29 preferably comprises a disk 31, of substantially the same diameter as the conveyer disk 27, the said disk 31 being adapted to overlie the conveyer face of the disk 27, and to abut against suitable projections 32 on the casing 1, and to contact with the end of the brass and wedge block, detachable retaining means being provided preferably between the said wedge block 17 and the disk 31, whereby to maintain the disk 31 in a stationary position with respect to the rotatable conveyer 27.

The retaining means for the disk 31 may take the form of pins or dowels, 33, projecting outwardly from the wedge block and adapted to fit within openings 34 in the disk 35 31. The disk 31 is provided with a central opening whereby it is spaced from the periphery of the journal, and said disk is also cut away at its bottom, as indicated at 36, whereby to expose one or more of the oil receptacles 29 when the latter are in oil receiving position in the oil chamber, provided by the journal box. The disk 31 is also provided with an opening 36 at the top thereof, said opening being adapted to afford direct 40 communication between the oil receptacles 29 of the disk 27 and the inlet port 22 leading to the inner surface of the brass 10.

The means for supporting the oil conveyer 27 upon the journal 11 preferably takes the form of laterally spaced bolts 37, loosely projecting through openings 38 in the disk 27 and having threaded terminals engaging the end of the journal 11. Spiral springs 37^a are positioned on the bolts, the same being interposed between the rear surface of the oil conveyer disk 27 and the headed end of said bolt. The function of these springs is to not only maintain the closure disk 31 in place, but to also maintain the conveyer 45 120

125 130

disk 27 in place, and the relative positions of these disks 27 and 31 will be substantially maintained while permitting of the necessary lateral vibration of the parts when in use.

The front wall 39 of the casing is provided with an upper movable section 40, the same having adjacent the center thereof, depending ears 41, adapted to overlie eyes 42 on the lower section of the rear wall, a suitable pintle 43 projecting between the ears 41, and a spiral spring 44 being positioned on said pin with opposite ends thereof engaging respectively the upper and lower section, whereby to maintain the upper movable section in closed position. The upper section 40 is provided with a hand engaging piece 45 whereby said section may be readily opened and closed. Through this opening the various operative parts of the journal box may be readily removed as occasion demands.

The operation of the device will probably be understood from the description above, but may be briefly reviewed as follows:— By reason of the particular shape of the casing, the cylindrical portion thereof in which is positioned the conveying mechanism forms an enlarged portion of the oil reservoir, and the substantially rectangular flatsided portion 2 of said casing makes the same readily applicable by means of securing bolts or straps to various pedestals.

The journal box, when applied in position, and having received a supply of oil will be so arranged that the end of the journal 11 fits within the annular recess or bearing 28 of the oil conveyer 27 with the cut off or closure disk 31 arranged in stationary position between the oil conveying means and the brass. The oil conveying means being relatively fixed with respect to the journal, will be rotated thereby whereby each oil pocket or receptacle 29 will pick up a supply of oil and in the continued rotation thereof, will be moved behind the overlying cut off disk 31 to the end that the oil will be carried by the receptacles 29 into position to discharge through the opening 36 of the disk 31, thence through the port 21 of the wedge block, for distribution to the oil ways of the brass. The supply of oil in the receptacle is preferably maintained to a height whereby it overlies the upper edge of the lowermost pocket 29, to the end that the oil will have no opportunity of leaving the receptacle 29 until the same has moved to a closed position behind the disk 31.

Should it be desired to remove any of the parts of the journal box, the hinge section 40 is moved to open position, and the bolts 37 removed from the journal 11, thereby permitting the disks 27 and 31 as well as the wedge block 17 and brass 10 to be easily removed through the opening provided in the

end wall 39. By rotating the bolts 37, the springs 37^a will be adjusted to regulate the tension, and as before described, the springs, with the bolts, form yieldable means for maintaining the disks 27 and 31 in proper position with respect to one another while permitting of the necessary vibration in the operation of the device.

From a reference to Fig. 1, it will be observed that the oil conveyer disk 27 is so positioned within the journal box that the lower edge thereof is separated from the bottom of the journal box casing a sufficient distance to permit of any dust, grit or the like to settle to the bottom of the journal box, to the end that the same will not be picked up by the conveyer 27 and fed with the oil to the journal.

I claim:—

1. In a journal box, the combination of a casing having an enlarged outer end forming an oil well, a journal or shaft projecting into the casing, a brass adapted to engage the upper surface of the end of a shaft positioned in the journal box, a wedge block interposed between the brass and the top of the journal box and having a detachable interlocking engagement with the brass, a disk-shaped guard plate having a central opening to engage over the end of the shaft, a detachable connection between the disk-shaped plate and the wedge block, said plate having an opening adjacent the upper edge thereof and said brass and wedge block having openings communicating with the opening in the plate whereby to convey oil from said opening to the shaft, and an oil conveyer disk having in its inner face a central recess to engage over the end of the shaft and in the same face adjacent the periphery thereof an annular recess divided by transverse partitions into a series of oil pockets, the first mentioned disk plate being of a size to overlie said pockets to constitute a closure therefor, and having a cut away portion adjacent its lower edge whereby to expose one of the pockets, means for detachably securing the oil conveyer disk to the end of the shaft, and said journal box having a movable closure in the end wall thereof permitting removal of each of said parts comprising the conveyer disk, the guard plate, the wedge block and brass.

2. In a journal box adapted to contain a supply of oil, the combination of a journal, a rotatable disk-shaped oil conveyer adapted to be connected to the outer end of a journal and having in its inner face adjacent to, but spaced from, the periphery thereof a series of pockets to convey oil from the oil supply to a point of discharge above the journal, and disk-shaped means acting automatically to close the pockets after receiving a supply of oil and maintain the pockets closed until reaching its point of discharge

above the journal, and means for yieldably supporting both the oil conveyer and pocket closure disk in position.

3. In a journal box, a rotatable oil conveyer wheel having in its face an oil space, and a disk-shaped cover adapted to normally entirely close said space, said cover being constructed and arranged to open the oil space when the same is in position to receive and discharge the oil, the disk cover having a central opening to receive the journal, and the conveyer wheel having a recess to receive the end of the journal, and means for detachably supporting both the disk and conveyer wheel in place.

4. In a journal box, an oil conveyer disk movably mounted to rotate about a horizontal axis and having on its inner surface an oil receiving recess, a relatively stationary member overlying the inner surface of the rotatable member and having an opening to expose said recess to permit the deposit of oil therein, and said stationary member also having an opening permitting discharge of the oil from said recess in the movement of the said rotary member, the stationary member acting to entirely close said recess when moving from one opening to another, the stationary member and disk being relatively movable and common means for maintaining both in position.

5. In a journal box, a journal, an oil conveying member comprising a rotatable disk having a central recess in one face adapted to receive the end of the journal positioned in the box, said disk having in its face a plurality of oil chambers, a stationary disk-shaped cover overlying said inner surface of the rotatable disk and adapted to entirely close a plurality of said openings, and said stationary disk having an opening adjacent the top and bottom thereof to register with said oil chambers in the rotation of the latter, and a detachable yieldable connection between the end of the journal and disk.

6. In a journal box, a journal, an oil conveying member comprising a rotatable disk adapted to be detachably connected to the end of the journal positioned in the box and having in one face a central recess to receive the end of the journal, said disk having in said face a plurality of oil chambers, a stationary disk-shaped cover overlying said inner surface of the rotatable disk and adapted to normally close said chambers, and said stationary disk having an opening adjacent the top and bottom thereof to register with said oil chambers in the rotation of the latter, means for yieldably holding said disks in contact, and means whereby both said disk and cover may be bodily detached.

7. In a journal box, a journal, a disk having in its inner face adjacent the periphery

thereof an annular recess divided by partitions into a series of pockets, a wedge block adapted to be interposed between the journal and top of the journal box, a closure disk for said pockets, a detachable connection between the wedge block and the closure disk, the closure disk having an opening adapted to register with the pockets, and the wedge block having an opening in communication with the opening of the closure disk, and means engaging the journal to detachably and yieldably secure the oil conveyer disk and the closure disk in position.

8. In a journal box adapted to receive the end of a journal, the combination of a journal, a brass adapted to rest upon the upper surface of the journal, a detachable wedge block interposed between the upper surface of the brass and inner surface of the journal box wall, an interlocking engagement between the brass and wedge block, a disk-shaped conveyer having in one surface thereof a series of oil conveyer pockets, a detachable connection between the conveyer and the end of the journal, a disk-shaped cover for the oil pockets, a detachable connection between the cover and the wedge block, and communicating ports in the wedge block and brass communicating with an opening in the cover disk, which last mentioned opening registers with the oil conveyer pockets.

9. In a journal box, adapted to receive the end of a journal, the combination of a journal, a brass adapted to engage the upper surface of the journal, the said brass having an opening projecting therethrough intermediate its ends, and oil ways leading from said intermediate opening, a wedge block interposed between the brass and top wall of the journal, said wedge block having an opening communicating with said intermediate opening of the brass, and a rotatable oil conveyer disk having on its inner surface a plurality of oil receiving chambers, a cut off disk overlying said inner surface of the conveyer member, pins projecting from the wedge block, and the cut off disk having recesses to receive said pins, substantially as and for the purpose described.

10. In a journal box, the combination of a journal box casing, having a substantially rectangular portion connecting with an enlarged substantially cylindrical outer end portion, a journal, a brass adapted to be positioned on the upper surface of the journal and having oil distributing ports on its inner surface, a wedge block interposed between the brass and the top wall of the journal box casing, a disk-shaped oil conveying member arranged in the cylindrical portion of the casing, and a disk-shaped guard interposed between the oil conveying member and end of the journal, the said

wedge block and disk-shaped guard having communicating openings whereby to receive oil from the conveying means and conduct the same to the distributing ports of the brass, a detachable connection between the disk-shaped guard and the wedge block, and a yieldable connection between the conveying means and terminal of the journal.

In testimony whereof I hereunto affix my signature in the presence of two witnesses.
